UNITED STATES PATENT OFFICE.

PETER RODIER, OF SPRINGFIELD, MASSACHUSETTS; FLAVIE M. RODIER
ADMINISTRATRIX OF SAID PETER RODIER, DECEASED.

SKATE.

SPECIFICATION forming part of Letters Patent No. 597,744, dated January 25, 1898.

Application filed February 27, 1893. Serial No. 463,956. (No model.)

To all whom it may concern:

Be it known that I, PETER RODIER, a citizen of the United States, residing at Springfield, in the county of Hampden and State of Massachusetts, have invented a new and useful Improvement in Skates, of which the following is a specification, reference being had to the accompanying drawings, forming part thereof.

10 The object of my invention is to provide a skate of improved construction which can be securely fastened to a boot or shoe without the aid of straps and without the use of a wrench or other tool independent of the skate 15 itself.

A further object is to provide means for clamping the front portion of the skate in position which will have the capacity of self-adjustment to enable it to conform itself to 20 the shape of the sole to which it is applied and to bear evenly against the latter throughout the entire length of said clamping means.

Other objects are to lessen the cost of manufacture of the skate and to provide means 25 whereby both the toe and heel clamping devices are operated by the movement of a single lever.

To these ends my invention consists in the 30 skate constructed as hereinafter fully described, and particularly pointed out in the claims.

Referring to the drawings, in which like letters and numerals designate like parts in the several views, Figure 1 is a side view of a skate embodying my invention. Fig. 2 is a bottom plan view thereof. Fig. 3 is a top plan view thereof with the clamping devices shown in their inoperative positions by broken lines. Fig. 3' is a view in perspective of a portion 35 40 of the heel-pedestal and of the bottom plate of the heel-clamping means. Figs. 4, 5, and 6 are corresponding views of another form of the invention. Figs. 7 and 8 are respectively a plan and an end view of the bottom plate 45 50 of the heel-clamping means shown in Figs. 4, 5, and 6. Fig. 9 illustrates a slightly-modified form of said heel-clamping means. Figs. 10, 11, and 12 illustrate still another modification of said heel-clamping mechanism, Fig. 50 10 showing the bottom plate, Fig. 11 the heel-pedestal of the frame, and Fig. 12 a side view

of a portion of said pedestal and the upper and bottom plates thereon. Figs. 13 and 14 are respectively a side and an end view of the claw which engages the front side of the 55 heel. Fig. 15 is an inverted perspective view of one of the side clamps for the front portion of the skate. Fig. 16 is a plan view of a portion thereof, showing the manner of securing the adjusting-screw in its bearings. 60

The letter *a* designates the frame of the skate, which is preferably formed from a single piece of metal by drop-forging or other process, and is so shaped as to form a toe-pedestal 2 and a heel-pedestal 3, with a depression 4 between them, said frame terminating at its front end in a depending brace 5 and at its rear end in two depending braces 6 7 and having in the plane of the depression 4 a fourth brace 8, each of which braces 70 is recessed at its lower end to receive the runner *b* and bored transversely to receive the screws or rivets by which said runner is fastened to the frame. The frame thus made is possessed of great strength and presents a 75 light and pleasing appearance, and by tying the runner thereto at each end and also between the toe and heel pedestals the runner is rigidly held from lateral deflection and is prevented from being cracked or broken by 80 heavy blows upon the ice. A further advantage secured by this form of frame is that it enables the runner to be readily removed from the frame for grinding or other purposes and enables a long runner for fast skating to be 85 substituted for the ordinary runner quickly and conveniently.

To the toe-pedestal is secured by screws 9 a sole-plate *c*, and to the under side of said sole-plate, near one of the side edges thereof, 90 is secured by rivets or otherwise one of the two side clamps *d* *d'*. The side clamp *d* (shown detached in Figs. 15 and 16) is composed of the base-plate 10, which receives the rivets by which the clamp is secured to the sole-plate, said base-plate being provided with a depending flange 12, in which is journaled an adjusting-screw 13 in such manner as to revolve without endwise movement, a slotted plate 14, embracing a guiding-stud 100 15 on the base-plate and provided at its inner end with a depending lug 16, which is

tapped to receive said screw 13, and at its outer end with an upwardly-projecting and threaded post 17, and a clamping-jaw 18, provided midway between its ends with a 5 tapped hole to receive said post and having an inwardly-projecting lip to overlie the edge of the sole of the shoe. By turning screw 13 the jaw 18 can be adjusted toward and away from the sole-plate *c* in a horizontal 10 plane, and by turning said jaw about the post 17 it can be raised and lowered to correspond to any thickness of sole, while its freedom to rock upon said post as a center causes it to adapt itself to a sole of any shape 15 and to bear against the edge thereof throughout its entire length, thereby insuring a firm hold upon the sole under all circumstances. Such capacity of said clamping-jaw to conform itself to soles of any shape forms an 20 important feature of my invention, and I do not wish to restrict myself to the precise means for securing to it such function herein shown and described, as other forms of means for such purpose can be employed within the 25 spirit of my invention.

With a view to cheapening the cost of manufacture I prefer to mill or otherwise form upon the shank of the adjusting-screw 13 the groove or recess 19 (see Fig. 16) and to provide the base-plate 10 and its flange 12 with the opening 20, whereby said screw can be passed within said opening in such manner as to cause the side edges of the opening in the flange 12 to project into the groove 19 in 30 the screw, and thus form a bearing for the latter which will permit it to revolve without endwise movement. I also prefer to provide the clamping-jaw 18 with a longitudinal slit 21, as shown, extending for a short distance 35 upon either side of the tapped hole therein to cause said jaw to have a pinching action upon the threaded post 17, and thus prevent sufficient looseness to enable the jaw to work itself off from the post, while affording it entire freedom to conform itself to the shape of a shoe-sole, as before described. The opposite side clamp *d*' instead of being connected to the sole-plate is mounted upon the locking-lever *e* and is identical in its construction 40 with the clamp *d*, except that the base-plate 10 is omitted, said lever itself forming the base-plate and having a depending flange 22 projecting therefrom, which corresponds to the flange 12 and forms a bearing for the adjusting-screw. As shown in Figs. 1, 2, and 3, the lever *e* is pivoted at its front end to the under side of the sole-plate and has its rear end extended slightly beyond the rear end of the latter and provided with a finger-piece 45 23. Adjacent to its rear end the lever is provided with a hole 24, (see its dotted position in Fig. 3,) which is adapted to receive a downwardly-projecting and inwardly-bent lug 25 on the sole-plate when the lever is in its closed position to lock it in such position, said lug 25 being preferably formed by stamping out and bending downwardly a portion of the

metal composing the sole-plate, as shown, to lessen the cost of manufacture and increase the strength and durability thereof.

It will be obvious from an inspection of Figs. 2 and 3 that when a shoe-sole is compressed between the side clamps *d* *d*' by forcing the locking-lever to its closed position said lever cannot be released except by a sufficient 75 farther inward movement thereof to disengage it from the lug 25, the lateral pressure of the sole against the side clamps serving to increase the tightness of the locking action between the lever and said lug. It follows, 80 therefore, that while the lever can be readily and instantly released by inward pressure thereon with the thumb or finger it cannot by any possibility be accidentally released during the act of skating, wherein the skate 85 devised by me differs materially from most of the skates heretofore used. The side clamps being once adjusted laterally and vertically to correspond with the width and thickness of the shoe-sole, a single movement of the 90 locking-lever toward the foot serves to fasten the front portion of the skate to the shoe, and a single movement thereof in the opposite direction serves to release the same, for which purpose it is unnecessary to remove a glove 95 or mitten from the hand which operates said lever.

The heel-clamping means shown in Figs. 1, 2, and 3 are independent of the toe-clamping means and are similar in their mode of operation to the heel-clamping means shown and described in Letters Patent No. 164,039, issued to me June 1, 1875. Said means consist of a bottom plate *f*, which rests upon the heel-pedestal 3 and is provided with a centrally-disposed oblong opening *f*² and with a short slot *f*³, leading from said opening, into which projects a stud *f*⁴, located slightly to one side or the center of the heel-pedestal, and an upper plate *f*', which rests upon the plate *f*, a screw 100 26, passing through a centrally-located hole in the plate *f*' and through the oblong opening in plate *f* into the pedestal 3, securing said plates upon the latter, while permitting them to have a swinging movement about the screw 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 the rear portion of the heel to firmly lock the heel end of the skate to the shoe. By swinging said plates to the position shown by broken lines in Fig. 3 the eccentric action of the stud on the pedestal within the transverse slot in the plate *f* causes a forward movement of said plate, as in my aforesaid previous patent, thereby causing a separation of the claw 29 from the spurs 31 to permit the heel to be inserted between them, and by swinging the skate into alignment with the bottom of the shoe the plate *f* and said claw are carried rearwardly again and the heel is securely clamped between the claw and spurs, all as clearly described in my previous patent. By utilizing the screw 27 to secure the adjustment of the claw to adapt the skate for use upon any size of heel, instead of the screw-bolt and nut and ratchet-plate described in my prior patent, I enable said adjustment to be made much more easily and quickly and avoid the necessity of carrying a wrench for turning said nut.

While the skate constructed as thus far described is adapted to be quickly and conveniently secured to and removed from the shoe and when so secured is firmly held in position without requiring the use of straps, I prefer to provide means whereby the heel-clamping means are operated to grasp and release the heel of the shoe by the movement of the locking-lever *e*, and for this purpose I make the upper plate *f'* of the heel-clamping means the movable plate and make the bottom plate stationary, as shown in Figs. 4, 5, and 6. The bottom plate *f* is rigidly secured to the pedestal 3 by two screws 32, the heads of which project upwardly within a longitudinal slot 33 in the upper plate *f'* and assist in guiding the movement of said upper plate in a right line. Said bottom plate is provided with two longitudinal slots 34, (see Fig. 7,) through which pass screws 35, which enter the upper plate and secure it in position, while permitting it to have the sliding movement just described. To the front end of the stem of the upper plate is connected, by a rivet or otherwise, the rear end of a tie-strip *g*, which strip passes forwardly beneath the sole-plate, being provided with longitudinal slots 36 to receive the screws 9, by which said plate is fastened to the pedestal 2, and at its front end is provided with a rounded projection 37. The locking-lever *e* is provided with a lateral projection at its front end, which projection terminates in a rounded socket to receive the projection 37 on said tie-strip, thereby forming a free hinge-joint between said lever and tie-bar; but any form of pivotal connection between said parts can be employed. Washers 38 are interposed between the sole-plate and the pedestal 2 and surrounding the screws 9, whereby a sufficient degree of separation between them is secured to permit the tie-bar to slide freely, and it follows from the construction just described that when the locking-lever is thrown

outwardly to open the side clamps the tie-bar and plate *f'* will be thrust rearwardly to open the heel-clamping devices, and that when said locking-lever is moved to its closed position the tie-bar and plate *f'* will be drawn forwardly and the heel of the shoe will be clamped between claw 29 and spurs 31. The skate can thus be clamped to or released from the shoe by a single movement of the locking-lever.

In Fig. 9 a single screw 39 is utilized to fasten the plate *f* to the heel-pedestal and assist in guiding the plate *f'* instead of the two screws 32, and the plate *f* (see Fig. 10) has an enlarged central orifice 40 to receive a tapped hub 41 on the heel-pedestal, (see Fig. 11,) which hub receives said screw 39, whereby when said parts are assembled, as shown in Fig. 12, the two plates *f f'* are capable of a rocking movement about said hub as a center in addition to the right-line movement of the plate *f'*. Provision is thus made for utilizing other forms of connections between the plate *f'* and the locking-lever than the tie-strip *g* or for locating said tie-strip to one side or the other of the central line of the skate should it be desired to do so.

The adjusting-screws 13 and 27 are preferably provided with milled heads, as shown, thereby enabling all of the adjustments of the skate to be made easily and quickly and without the use of a wrench or other tool independent of the skate itself. The skate constructed as herein described is very strong and durable, quickly and easily operated, and presents a light and graceful appearance.

It will be obvious that the toe and heel clamping devices herein shown and described can be applied either to a runner-skate or to a roller-skate, and they are not dependent for their perfect operation upon the particular form of frame and runner herein shown.

Having thus fully described my invention, what I claim, and desire to secure by Letters Patent, is—

1. A skate provided with clamping-jaws adapted to overlap the opposite edges of a shoe-sole, each of which jaws is supported between its ends upon a vertically-disposed pivot and is thereby rendered capable of a rocking movement in a horizontal plane, and having means for adjusting said jaws both vertically and horizontally, substantially as set forth.

2. In a skate, the combination with a sole-plate, of a locking-lever pivotally connected to said plate, two clamping-jaws for engaging the sides of a shoe-sole, one of which is mounted upon said sole-plate and the other upon said lever, and means substantially as described for securing a horizontal adjustment of said jaws upon their supports, substantially as and for the purpose set forth.

3. In a skate, the combination with the sole-plate, of a locking-lever pivoted at its front end to the under side of said plate and provided at its rear end with means for mak-

- ing a locking engagement with said plate, two clamping-jaws mounted upon said sole-plate and lever respectively each of which is adapted to overlap the edge of a shoe-sole 5 and is capable of a rocking movement in a horizontal plane, and means for securing an independent adjustment of said jaws to vary the distance between them, substantially as set forth.
10. 4. In a skate, the combination with a sole-plate having a depending lug formed by stamping out and bending downwardly and inwardly a portion of the body of said plate, a locking-lever pivotally connected at its 15 front end to said plate and provided near its rear end with an opening to receive said lug, and two side clamps for a shoe-sole, one of which is mounted upon said sole-plate and the other upon said lever, substantially as set forth.
15. 5. In a skate, the combination with a sole-plate, of a laterally-swinging locking-lever pivotally connected thereto, two clamping-jaws adapted to overlap the side edges of a 20 shoe-sole, one of which is mounted upon said plate and the other upon said lever, means for independently adjusting said jaws both laterally and vertically upon their supports, and suitable heel-clamping devices for engaging 25 a shoe-heel, substantially as set forth.
20. 6. In a skate, the combination with a sole-plate, of a locking-lever pivotally connected thereto, two sliding plates mounted upon the under sides of said sole-plate and lever respectively each of which carries at its outer 30 end a vertically-disposed post, means, as adjusting-screws, for governing the lateral position of said plates, and two clamping-jaws mounted upon said posts respectively in such 35 manner as to be capable of a rocking movement in a horizontal plane, substantially as set forth.
25. 7. The combination with the sole-plate and the locking-lever pivotally connected thereto, of the adjustable side clamps mounted upon said plate and lever respectively, heel-clamping means comprising a stationary claw and a movable plate carrying spurs adapted to cooperate with said claw to clamp a shoe-heel 40 between them, and an intermediate connection between said movable plate and said 45
- locking-lever substantially as described, whereby the side clamps and heel-clamps will be operated simultaneously by the movement of said lever. 55
8. The combination with a sole-plate, as *c*, locking-lever, as *e*, and side clamps, as *d d'*, carried by said plate and lever respectively, of an adjustable, heel-engaging claw, as 29, a spur-carrying plate, as *f'*, adapted for movement toward and away from said sole-plate, and a rigid connection, as the tie-strip *g*, between said plate and said locking-lever, substantially as and for the purpose set forth. 60
9. The combination with the heel-pedestal 65 3, of the plate *f* mounted upon said pedestal and having a forwardly-projecting stem, plate *f'* guided for longitudinal movement upon the plate *f* and having a projecting stem which overlies the stem of the latter, claw 29 mov- 70 ably mounted upon the stems of said plates, and adjusting-screw 27 revolvably supported upon the stem of said plate *f* and entering a tapped hole in said claw, substantially as described. 75
10. The combination with the plates 14 carrying the threaded posts 17, and the adjusting-screws 13 operatively connected therewith, of the clamping-jaws 18 provided with a tapped hole to receive said posts, substan- 80 tially as and for the purpose described.
11. The combination with the threaded posts 17, of the clamping-jaws 18 having a tapped hole to receive said posts and provided with a slit extending longitudinally thereof 85 upon opposite sides of said hole, substantially as and for the purpose described.
12. The combination with the base-plate 10 having the flange 12 and provided with the opening 20, of the plate 14 guided for move- 90 ment upon said base-plate and having the flange 16, screw 13 having the groove 19 in the shank thereof whereby it is adapted to be inserted and revolvably held within said flange 12, said screw entering a tapped hole in the 95 flange 16, and the clamping-jaw 18 carried by said plate 14, substantially as described.

PETER RODIER.
